UNITED STATES PATENT OFFICE.

JACOB B. BANDER, OF NEW YORK, N. Y.

SHADE HOLDER FOR ELECTRIC-LIGHT FIXTURES.

Application filed February 6, 1925. Serial No. 7,318.

REISSUED

This invention relates to devices for holding light shades such as are commonly used in connection with the sockets of incandescent electric lights.

One important object of the invention is to improve the general construction of devices of this character.

A second important object of this invention is to provide an improved device of this kind which may be used either for closed or open glassware such as globes or bell shaped shades.

A third important object of the invention is to provide a device of this character having novel construction by means of which the device may be made to support the lamp shade without the use of screws bearing against the shade and without screwing any of the parts together.

A fourth important object of the invention is to provide a device of this character having a novel arrangement of tilting arms and fingers supported on the main part of the device in an improved manner, the support itself limiting the tilting movement of such arms and fingers.

A fifth important object of the invention is to provide a novel stop arrangement for the tilting arms and fingers which will also act as a stop for the means employed to retain the fingers in their expanded or spread position.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the complete device showing one form of glass shade secured thereto, the lower part of the latter being broken away.

Figure 2 is a similar view with the glass shade removed, its position being shown merely in dotted lines.

Figure 3 is a view of the device with the bell or outer part removed and the tilting fingers in their contracted position.

Figure 4 is a section on the line 4—4 of Figure 1.

Figure 5 is an enlarged detail section on the line 5—5 of Figure 4.

Figure 6 is an enlarged detail vertical section showing the manner in which the combined support and stop acts when the fingers are tilted.

Figure 7 is a detail section showing a certain spring for retaining the bell in position.

In the present embodiment the invention consists of three general parts, an inner shell, arms tiltably connected to the inner shell and a bell having a portion arranged to force the arms against the inner shell and hold them in such position, the arms carry fingers which are expanded when the arms are against the inner shell and collapsed when the arms move outward.

In the drawings there is disclosed an inner shell 10 having its upper edge curved inwardly to form a top portion 11 provided with a central opening 12 wherethrough may pass shank 13 of a socket 14, stop for holding an incandescent lamp 15. Fitted over this inner shell 10 is a series of arms 16 each of which has its upper end curved inward as at 17 to fit over the curved portion 11 of the inner shell and which butts against a shoulder 18 at the top of the inner shell, the outer surface of the arm at this point being flush with the upper edge of the shoulder.

Each of these arms carries on its lower end an outwardly and downwardly projecting finger 19 having a portion adjacent its extremity bent downward as at 20 and its bent outward extremity as at 21, the parts 20 and 21 thus forming a shoulder so that a shade or globe 22 having the usual top opening 23 may rest on the parts 21 and be held centrally positioned by the parts 20. In order to expand each of these arms and its finger there is provided for each arm a lower supporting tongue 24 turned upward and inclined outwardly as at 25 at its extremity. There is also provided an upper supporting tongue 26 having an upwardly and outwardly inclined extremity 27. These tongues are struck out of the body of the shell 10 adjacent its lower end and this construction can best be seen by reference to Figure 6. Each tongue passes through a suitable opening 28 in the respective arm and by reference to the said figure it will be seen that the upturned portions 25 and 27 of the tongues form limit stops for limiting the outward tilting of the arm 16. At 29 is a bell having a contracted end 30 which slidably fits over the arms 16 and draws them together

as shown in Figure 4. This, of course, expands the group of fingers 19 so that while the parts, in the position of Figure 3, are so arranged that the group of arms may pass through the shade opening 23, yet, when the bell is applied, these fingers are so expanded as to grip beneath the shade 22 on its inner or under side. It will be noted from Figure 4 that parts 27 also form limit stops for preventing the bell from passing down too far. The bell preferably has a depending skirt 31 which rests on top of the shade 22 adjacent the opening 23 and thus holds the shade against moving loosely on the arms. A spring catch is used to prevent the bell from accidentally slipping upward.

In use the spring catch is pushed in and the bell drawn up to free the arms 16. The fingers are then inserted into the opening 23 of the shade and the bell pushed down over the arms thus securing the shade in position. Now, there has been here shown three of the arms 16, but it is clearly to be understood that the invention is not limited to the use of three arms. For instance, with heavy shades, a larger number of arms is preferable and in certain instances six or even eight arms may be found desirable. It is deemed unnecessary to show these various numbers of arms as the construction on which the invention is based will remain the same in each case.

In order to make certain that the wings open properly a spring 33 is provided. This may either be a leaf spring such as is shown in Figure 6 or it may be a coil spring wound around the member 26.

Furthermore, it is to be noted at the bottom of the skirt 31 a bead 32' is preferably provided on which may rest a suitable reflector 33', the device being thus capable not only of being used to support a bell or globe shaped shade but also to support any desired type of reflector.

It will also be observed that this bead may be used to support an ornamental band or hood.

There has thus been provided a simple and efficient device of the kind described and for the purpose specified.

It is obvious that minor changes may be made in the form and construction of the invention without departing from the spirit thereof. It is not, therefore, desired to confine the invention to the exact form herein shown and described, but it is desired to include all such as properly come within the scope claimed.

Having thus described the invention, what is claimed as new, is:

1. In a shade support, the combination with an inner shell adapted to receive a lighting fixture and having a cylindrical body; of a series of arms arcuate in cross section and surrounding said shell, means

on the lower end of said shell to support the lower parts of said arms for swinging movement of the upper ends of the arms to and from the shell, each of said means being provided with a limit stop engaging the outer surface of the respective arm to limit the outward movement of its upper end, said means each including a tongue extending rigidly and radially from the shell through the lower part of the respective arm and having an upturned extremity to engage the outer surface of said arm, other limit means above the last mentioned means and each including a similar but longer tongue extending through the respective arm above the first means and provided with a similar upturned extremity, a finger on the lower end of each arm extending radially from the shell, said fingers being arranged to support a lamp shade at their extremities, and a bell slidable over said arms to hold them against the shell and the fingers expanded.

2. In a shade support, the combination with an inner shell adapted to receive a lighting fixture and having a cylindrical body; of a series of arms arcuate in cross section and surrounding said shell, means on the lower end of said shell to support the lower parts of said arms for swinging movement of the upper ends of the arms to and from the shell, each of said means being provided with a limit stop engaging the outer surface of the respective arm to limit the outward movement of its upper end, said means each including a tongue extending rigidly and radially from the shell through the lower part of the respective arm and having an upturned extremity to engage the outer surface of said arm, other limit means above the first means and provided with a similar upturned extremity, a finger on the lower end of each arm extending radially from the shell, said fingers being arranged to support a lamp shade at their extremities, and a bell slidable over said arms to hold them against the shell and the fingers expanded, said bell having a lower peripheral portion lying above the outer ends of said fingers upon the latter being expanded whereby to engage the outer surface of the shade, the upturned ends of the second limit means being positioned to engage the inner surface of said bell and limit the downward movement thereof.

3. In a shade support, the combination with an inner shell adapted to receive a lighting fixture and having a cylindrical body; of a series of arms arcuate in cross section and surrounding said shell, means on the lower end of said shell to support the lower parts of said arms for swinging movement of the upper ends of the arms to and from the shell, each of said means being provided with a limit stop engaging the outer surface of the respective arm to limit the

outward movement of its upper end, said means each including a tongue extending radially from the shell through the lower part of the respective arm and having an upturned extremity to engage the outer surface of said arm, other limit means above the first means and provided with a similar upturned extremity, a finger on the lower end of each arm extending radially from the shell, said fingers being arranged to support a lamp shade at their extremities, and a bell slidable over said arms to hold them against the shell and the fingers expanded,

said bell having a lower peripheral portion lying above the outer ends of said fingers 15 upon the latter being expanded whereby to engage the outer surface of the shade, the upturned ends of the second limit means being positioned to engage the inner surface of said bell and limit the downward movement 20 thereof, and a spring latch carried by the shell and engaging the upper edge of the bell to hold the bell against accidental upward movement.

In testimony whereof I affix my signature.
JACOB B. BANDER.
